CLAIM

The ornamental design for an automobile vacuum cleaner, substantially as shown and described.

DESCRIPTION

FIG. 1 is a perspective view of an automobile vacuum cleaner showing our new design and shown with a hose and nozzle in broken lines for illustrative purposes only; FIG. 2 is a top plan view thereof, shown on a larger scale; FIG. 3 is a right side elevational view, the left side being a mirror image thereof; FIG. 4 is a rear elevational view thereof; FIG. 5 is a front elevational view thereof; and FIG. 6 is a bottom plan view thereof.

FIG. 2

FIG. 1

FIG. 4

FIG. 3

FIG. 6

FIG. 5
